Specification for Design.

Patented May 18, 1920.

Application filed December 11, 1919. Serial No. 344,145. Term of patent 14 years.

To all whom it may concern:

Be it known that I, ALFRED H. HUMPHREY, a citizen of the United States, and a resident of the city and county of New York, State of New York, (whose post-office address is 44 West Broadway, New York city,) have invented a new, original, and ornamental Design for Gas-Stoves, of which the following is a specification, reference being had to the accompanying drawing, forming a part

thereof, which is a front view of a gas-stove showing my new design.

I claim:

The ornamental design for a gas stove as shown.

ALFRED H. HUMPHREY.
